UNITED STATES PATENT OFFICE.

MAURICE B. LONG, OF GLEN RIDGE, NEW JERSEY, ASSIGNOR TO WESTERN ELECTRIC COMPANY, INCORPORATED, OF NEW YORK, N. Y., A CORPORATION OF NEW YORK.

MULTIPLEX SIGNALING SYSTEM.

Application filed February 20, 1924. Serial No. 693,998.

To all whom it may concern:

Be it known that I, MAURICE B. LONG, a citizen of the United States of America, residing at Glen Ridge, in the county of Essex and State of New Jersey, have invented certain new and useful Improvements in Multiplex Signaling Systems, of which the following is a full, clear, concise, and exact description.

10 This invention relates to multiplex signaling systems employing a plurality of currents or waves of different frequencies for the transmission of signals or for similar purposes.

15 A general object of the invention is to provide a system in which a high degree of selectivity is obtained between the various message waves, with an accompanying economy in the frequency range, and in 20 which a more economical as well as a more efficient construction and arrangement of the various selective elements of the system is realized.

25 Another object of the invention is to reduce the number of different types of filters employed in such a system.

Another object of the invention is to simplify the design and construction of filters employed in such systems.

30 In multiplex signaling systems in which transmitted energy is in the form of waves or oscillations, modulated in accordance with the signals to be transmitted, a plurality of such waves, each of a distinctive frequency, are transmitted over the same line. In such systems, wave filters and in 35 some cases tuned circuits are used to separate the various distinctive frequencies, one from another.

40 It has been demonstrated that the transmission of several kinds of signals may be carried on at the same time in both directions through the system, the different kinds of signals and the different directions being 45 distinguished by the different frequencies employed. Such a system is disclosed in an application of J. W. Horton, Serial No. 488,297, filed July 29, 1921. In that system, the transmissions of an ordinary telephone line, Morse telegraph and other signaling currents within or below the ordinary telephone range are separated from the carrier transmissions by the use of broad band filters, or high frequency composite filters.

50 The carrier transmissions comprising te-

lephony and telegraphy are separated from each other by means of grouping filters.

Due to the inherent attenuation of the transmission line and its associated apparatus, it is necessary to amplify the transmitted signals. This may be accomplished by providing a repeater system in which oppositely directed waves are transmitted at different frequencies, grouping filters being provided at the repeater so that all of the waves transmitted in a given direction will be selectively transmitted to the repeater circuits that operate to amplify waves in that direction.

It has been suggested that economy in the construction of filters can be obtained by building each filter up from elements that are sufficient for the particular load requirements, such as the frequency, current strength and attenuation. This was particularly true of the older types of filters which required a large number of elements. Filters more recently developed employ a lesser number of elements but the saving in filter material is offset to a considerable extent by the greater cost of engineering such a system involving designing each filter from its individual requirements. According to the invention, it is found possible to retain the economy resulting from the individual design of the filters and at the same time very materially reduce the manufacturing and engineering costs of the system, thus securing material economy in construction without sacrificing efficiency or any of the advantages of former systems.

In a multiplex system to which the invention is particularly applicable, the repeater filters consist of a plurality of sections divided into two groups by means of an amplifier, thus connecting the repeater element to both ends of the line through sections of the selective filters. In such a system, the sections of one filter group have a higher transmission efficiency than those of the other group for the same load for the purpose of eliminating harmonics and intermodulation currents. The input and output repeater filters must be designed to transmit frequencies within a given range and to effectively suppress all frequencies outside of this range, and at the same time must have such an attenuation that the combined effect of the filters will prevent "singing" at the repeater for the desired range.

of transmission. Heretofore, to meet these requirements, grouping filters have been employed which have been separately designed with respect to their particular functions.

5 This has not only complicated the design and construction of the filters but has also necessitated the construction of a separate and distinct filter for each filter position in the system.

10 In accordance with a feature of the invention, the number of different types of filters in a multiplex signaling system of the above type is materially reduced by designing the filters in accordance with the 15 filter requirements at different points in the system.

Since the individual filters are located at different points in the system to accomplish different purposes, they accordingly have 20 different requirements, either individually or in groups, and in accordance with the invention one filter of a group is made identical with a single filter at another position and another filter of the group is so designed 25 that when combined with the other filter of the group the combination will meet the group requirements.

More specifically, the receiving grouping filter of the signaling system is first designed to meet certain given requirements 30 and an identical filter is used as the input filter of the repeater for the same group of frequencies. The output repeater filter is then so designed that the combined effect of the input and output repeater filters will prevent singing at the repeater. The output repeater filter is also designed to have a predetermined impedance requirement so that an identical filter can be used 40 as the sending grouping filter.

Other features and advantages of the invention will appear from the consideration of the following description taken in connection with the accompanying drawings, 45 in which,

Figs. 1, 2 and 3, when placed end to end in the order named, with Fig. 1 at the left, illustrate diagrammatically one embodiment of the invention. Fig. 1 shows 50 the carrier telegraph and carrier telephone apparatus at one terminal station; Fig. 2 the apparatus and selective circuits at a mid-line repeater station; and Fig. 3, the carrier telephone and carrier telegraph terminal apparatus at the other terminal station.

Referring to the drawings, the terminal station of Fig. 1, hereinafter called the west station, is connected to the terminal station shown in Fig. 3, hereinafter called the east station, by means of a common transmission line ML. The mid-line repeater station shown in Fig. 2 is connected into the common line ML.

60 The west terminal station is connected to

the common transmission line ML by means of a "high frequency composite set", comprising a high pass filter 10 and a low pass filter 11. These filters and others used throughout this system, unless otherwise 70 specifically mentioned, may be of the type disclosed in British Patent 186,198 and may be constructed as composite wave filters as disclosed in Part 3 of an article on the Theory and design of uniform and composite electric wave-filters, by Otto J. Zobel, in the Bell System Technical Journal, of January, 1923. These filters consist, in general of a plurality of sections having series and shunt reactances, designed, according 80 to well known laws, for the range of frequencies of the currents which the filters are to transmit. Filters of this type are known as suppression filters and are particularly advantageous where a sharp cut-off 85 between frequencies in the transmitted and suppressed ranges is desired. Filter 10 is adapted to pass with substantially negligible attenuation, all currents having frequencies of 3330 cycles and above, and to 90 greatly attenuate currents having frequencies less than 3330 cycles, while filter 11 is adapted to pass with substantially negligible attenuation, all currents having frequencies of 2800 cycles or less and to highly 95 attenuate all currents having frequencies above 2800 cycles. Such an arrangement of filters is shown in Fig. 15 of a paper entitled "Carrier current telephony and telegraphy" by E. H. Colpitts and O. B. Blackwell, published in the Transactions of the American Institute of Electrical Engineers, Volume 40, 1921. These filters serve to separate the normal transmission of an ordinary telegraph and telephone line L² from 105 the carrier transmissions of the carrier circuit CC².

In order to separate the carrier telegraph transmissions from the carrier telephone transmissions, filters 12 and 13 are provided. 110 Filter 12 is a low pass filter adapted to pass with substantially negligible attenuation, frequencies of 9000 cycles and under, and to highly attenuate all frequencies above that value. Filter 13 is a high pass 115 filter adapted to pass with substantially negligible attenuation frequencies of 10,000 cycles and above, and to highly attenuate all frequencies below that value. These filters will hereinafter be called "carrier 120 grouping filters".

For the carrier telegraph transmission, filters 14 and 15 are provided to separate the frequencies used for transmission from the west station from those used for reception thereat. Filter 14 is a low pass filter adapted to pass with substantially negligible attenuation, frequencies of 5500 cycles and under, and to highly attenuate all frequencies above 5500 cycles. Filter 15 is a high 130

pass filter adapted to pass the frequency of 6500 cycles and all frequencies above that value and to highly attenuate all frequencies below 6500 cycles. These filters will 5 hereinafter be called "carrier telegraph grouping filters". Filters corresponding to filters 14 and 15, and the associated transmitting and receiving apparatus, are also provided at the west station for the carrier 10 telephone transmissions.

Tuned selective circuits S^1 , S^2 , etc., are provided to separate the frequencies used for carrier telegraph transmitting at the 15 west station. If desired, wave filters may be used for this purpose instead of tuned 20 circuits. At the west station selective receiving circuits R^1 , R^2 , etc., are also employed. The selective telegraph transmitting circuits are coupled to the input of low pass filter 14 by means of transformer 16 and the selective receiving circuits are coupled to the high pass filter 15 by means 25 of transformer 17.

The carrier telegraph terminal apparatus 30 shown in Fig. 1 is similar to the terminal apparatus shown in Fig. 55 of the Colpitts and Blackwell paper, supra. The sending circuits each comprise an oscillator and amplifier 18 and a sending relay 19 connected to the respective selective sending circuits S^1 , S^2 , etc. The receiving circuits each comprise an amplifier and detector 20 and a receiving relay 21 connected to the respective selective receiving circuits R^1 , R^2 , etc. 35 The sending relay 19 and the receiving relay 21 are each associated with ordinary Morse telegraph apparatus in the manner well understood in the art.

At the carrier repeater station, shown in 40 Fig. 2, the low frequency telegraph and telephone line L^3 and the common carrier circuit CC^3 are connected to the common line ML by means of a high frequency composite set comprising the low pass filter 23 and the high pass filter 24. Filters 23 and 45 24 are similar respectively to filters 11 and 10. Carrier grouping filters are also provided and comprise a low pass filter 25 and a high pass filter 26. Filters 25 and 26 50 are similar respectively to filters 12 and 13 of Fig. 1. For repeating carrier telegraph signals east and west repeater elements TRE and TRW, respectively, are provided. Repeating elements suitable for this purpose 55 are described in connection with Figs. 21 and 22 of the Colpitts and Blackwell paper, supra. Carrier telegraph transmissions east are separated from transmissions west by low pass filters 27 and 28 and high pass 60 filters 29 and 30, respectively. Filters 27 and 28 are adapted to pass the same range of frequencies as filter 14 of Fig. 1, and filters 29 and 30 are adapted to pass the 65 same range of frequencies as filter 15 of Fig. 1. The arrangement of the repeater

filter in a plurality of sections divided into two groups by means of the amplifiers is in accordance with the invention disclosed in Patent No. 1,413,357 to P. A. Raibourn, April 18, 1922, all the sections cooperating 70 to selectively transmit currents of the desired range of frequencies to the exclusion of currents of other frequencies.

Carrier grouping filters 31 and 32 separate 75 the carrier telegraph transmissions from the carrier telephone transmissions at the east end of the repeater. Filters 31 and 32 are similar to and are adapted to pass the same range of frequencies as filters 12 and 13, respectively, of Fig. 1. A high frequency composite set comprising high pass filter 33 and low pass filter 34 is provided to connect the common carrier circuit CC^4 and the ordinary telegraph and telephone line L^4 to the common line ML . High pass filter 33 and low pass filter 34 are similar respectively to high pass filter 10 and low pass filter 11 of Fig. 1. At the repeater station are also provided carrier telephone repeater 80 elements corresponding to the carrier telegraph repeating elements described above.

The east station is similar in arrangement to the west station. A high frequency composite set comprising the high pass filter 35 and the low pass filter 36 connects the 90 common carrier circuit CC^5 and the ordinary telegraph and telephone line L^5 to the common line ML . Filters 35 and 36 correspond respectively to filters 10 and 11 of Fig. 1. Low pass filter 37 and high pass 95 filter 38 are the carrier grouping filters at the east station and correspond respectively to filters 12 and 13 of the west station. Low pass filter 39 and high pass filter 40 are the 100 carrier telegraph grouping filters designed to pass, respectively, the same band of frequencies as the low pass filter 14 and the high pass filter 15 of Fig. 1. The filter 39 is adapted to pass with substantially negligible attenuation all currents having frequencies of 5500 cycles and below, and to 105 greatly attenuate currents having frequencies above 5500 cycles, while filter 40 is adapted to pass with substantially negligible attenuation all currents having frequencies of 6500 cycles and above and to greatly attenuate currents having frequencies less than 6500 cycles. Selective transmitting circuits ES^1 , ES^2 , etc., are coupled to the high pass 110 filter 40 by means of transformer 41, and 115 correspond to the transmitting selective circuits S^1 , S^2 , etc., of the west station and cooperate with the receiving selective circuits R^1 , R^2 , etc., of that station. The receiving selective circuits ER^1 , ER^2 , etc., of 120 the east station are coupled to the low pass filter 39 by means of transformer 42, and 125 correspond to the receiving selective circuits R^1 , R^2 , etc., of the west station and cooperate with the transmitting selective circuits 130

S^1 , S^2 , etc., of that station. The carrier telegraph terminal apparatus at the east station is similar to that employed at the west station, each of the sending circuits including an oscillator and amplifier 43 and a sending relay 44, and each of the receiving circuits including a receiving relay 45 and an amplifier and detector 46 connected to the respective tuned circuits. Filters corresponding to filters 39 and 40, and the associated receiving and transmitting apparatus are also provided at the east station for the carrier telephone transmissions.

In accordance with the Raibourn patent, supra, the amplifiers TRE and TRW at the repeater station of Fig. 2 are interposed between the input and output repeater filters 27, 28 and 29, 30 respectively, so that part of the filter sections are connected to the input circuit of the amplifier and the remainder of the sections are connected to its output circuit. By means of this arrangement both units 27 and 28 and units 29 and 30 serve to prevent transmission of currents of the frequencies assigned to the other branch, and in addition units 28 and 29 serve to suppress harmonics and intermodulation currents produced by the repeater elements TRE and TRW, respectively, which are of frequencies outside the normal range of its respective branch. It has heretofore been the practice to construct each of the transmitting filters 14 and 40 and the receiving grouping filters 15 and 39 as well as the repeater filters 27, 28, 29 and 30 with respect to their own particular functions without regard to their combined relation in the system. As a result of this practice, a great many different types of filters have been necessarily employed. In accordance with a feature of the invention, the receiving and sending grouping filters and the input and output repeater filters for the same group of frequency are each designed with reference to the requirements of the others. The receiving grouping filter of each branch or channel has both an impedance and an attenuation requirement and is taken as a basis of design for all of the other filters. The input and output filters at the repeater must meet certain combined requirements, and therefore, the input filter is made identical to the receiving grouping filter and the output filter is so designed as to make the combination meet the combined repeater requirements. The transmitting grouping filter has mainly an impedance requirement and the output repeater filter is given this impedance requirement and can therefore be used as the transmitting grouping filter. By this arrangement two types of filters only are required for four filter positions in the system.

In the system herein shown and described, the receiving grouping filter 39 is construct-

ed in accordance with the impedance and attenuation requirements at this position. This filter may be of the composite wave filter type described in the Zobel article, supra, and consists of a plurality of sections having series and shunt reactances designed to give the filter the required impedance and attenuation characteristics. The values of the various elements of the filter 39 for the given range of frequencies is shown by way of illustration in the drawing. This filter is taken as a basis of design for the filters 14, 27 and 28. The input filter 27 and the output filter 28 at the repeater station must meet certain combined requirements. To meet these requirements the input filter 27 is made identical to the receiving grouping filter 39, as indicated in the drawings, and the output filter 28 is then designed to have such an attenuation that the combined effect of the filters 27 and 28 will prevent "singing" at the repeater for the desired range of transmission. The sending grouping filter 14 has mainly an impedance requirement and the output repeater filter 28 is given this impedance requirement, and therefore the sending grouping filter 14 may be identical to the output repeater filter 28.

The high pass grouping filters 15 and 40 and repeater filters 29 and 30 are constructed in the same manner as the grouping filters 14 and 39 and the repeater filters 27 and 28. The receiving grouping filter 15 is first constructed in accordance with its impedance and attenuation requirement and is taken as a basis of design for the filters 29, 30 and 40. The input repeater filter 30 is made identical to the receiving grouping filter 15 and the output repeater filter is so designed as to make the combined effect of the filters 29 and 30 meet the repeater requirements, taking into consideration the impedance requirement for the filter 40. The filter 40 is then made identical to the output repeater filter 29. By means of this arrangement, only two types of filters are required for the four filter positions 15, 29, 30 and 40, as well as two additional types of filters for the four filter positions 14, 27, 28 and 39.

The invention has been illustrated in connection with the carrier telegraph circuits of the multiplex signalling system, but it is to be understood that it is equally applicable to, and in fact has been successfully used in, the carrier telephone circuits, only so much of the carrier telephone circuits being shown as is thought necessary to a complete understanding of the invention. The transmitting and receiving grouping filters of the carrier telephone system corresponding to the transmitting and receiving carrier telegraph grouping filters 14, 40, 15 and 39, respectively, are not shown in the drawing, but may be so constructed with relation to

the input and output filters at the carrier telephone repeater, in accordance with the invention, that the number of types of filters required in the system is materially reduced.

The circuits and systems that have been illustrated and described in detail should be considered as merely typifying one form of the invention but are not to be construed as limiting the invention, the scope of which is defined by the appended claims.

What is claimed is:

1. In a multiplex signaling system, a transmission line, stations thereon, a grouping filter at one station, a grouping filter at another station, and a repeater connected in said line and comprising an input filter identical to one of said grouping filters and an output filter identical to the other of said grouping filters, said output filter having a different transmission efficiency for large currents than said input filter.

2. In a multiplex signaling system, a transmission line, stations thereon, a transmitting grouping filter at one station, a receiving grouping filter at another station, and a repeater connected in said line and comprising an input filter identical to said receiving grouping filter and an output filter identical to said transmitting grouping filter, said output filter having a higher transmission efficiency for large currents than said input filter.

3. In a multiplex signaling system, a transmission line, a grouping filter at one end of said line, a grouping filter at the other end of said line, and a repeater connected in said line and comprising a plurality of sections and an amplifier dividing said sections into two groups, the sections of one group being identical to one of said grouping filters and the sections of the other group being identical to the other grouping filter, the sections of the second group having a different transmission efficiency for amplified currents than the sections of the first group for the same load.

4. In a multiplex signaling system, a transmission line, a transmitting grouping filter at one end of said line, a receiving grouping filter at the other end of said line, and a repeater connected in said line and comprising a plurality of sections and an amplifier dividing said sections into two groups, the sections of one group being identical to said receiving grouping filter and the sections of the other group being identical to the transmitting grouping filter, the sections of the second group having a higher transmission efficiency for amplified currents than the sections of the first group for the same load.

5. In a multiplex signaling system, a transmission line, a grouping filter at one

end of said line, a plurality of transmitting channels connected to said filter, a second grouping filter at the other end of said line, a plurality of receiving channels connected to said second filter, and a repeater comprising input and output filters having different transmission efficiencies connected to said line, said input filter being identical to one of said grouping filters and said output filter being identical to the other of said grouping filters.

6. In a multiplex signaling system, a transmission line, a transmitting grouping filter at one end of said line, a plurality of transmitting channels connected to said filter, a receiving grouping filter at the other end of said line, a plurality of receiving channels connected to said receiving filter, and a repeater comprising input and output filters having different transmission efficiencies connected to said line, said input filter being identical to said receiving grouping filter and said output filter being identical to said transmitting grouping filter.

7. In a multiplex signaling system, a transmission line, a transmitting grouping filter at one end of said line, a plurality of transmitting channels connected to said filter to transmit currents of different frequencies through it, a receiving grouping filter at the other end of said line, a plurality of receiving channels connected to said receiving filter to receive currents of different frequencies transmitted through it, and a repeater comprising input and output filters having different transmission efficiencies connected to said line, said input filter being identical to said receiving grouping filter and said output filter being identical to said transmitting grouping filter.

8. In a multiplex signaling system, a transmission line, a transmitting grouping filter at one end of said line, a plurality of transmitting channels connected to said filter to transmit currents of different frequencies through it, a receiving grouping filter at the other end of said line, a plurality of receiving channels connected to said receiving filter to receive currents of different frequencies transmitted through it, and a repeater connected in said line comprising a plurality of sections and an amplifier dividing said sections into two groups, the sections of one group being identical to said receiving grouping filter and the sections of the other group being identical to said transmitting grouping filter, the sections of the second group having a higher transmission efficiency for amplified currents than the sections of the first group.

In witness whereof, I hereunto subscribe my name this 19th day of February A. D., 1924.

MAURICE B. LONG.
